John E. Bangs

ATTORNEY.

UNITED STATES PATENT OFFICE

2,086,673

STRIPPING DEVICE

Donald Johnson, Milwaukee, Wis.

Application March 8, 1935, Serial No. 10,112

1 Claim. (Cl. 91—43)

My invention relates to striping devices and more particularly to a type of device that is used for marking athletic fields for games such as football, tennis, baseball and the like, or for marking traffic lines on highways or roads.

The object of my invention is to provide a means for conveying the lime or other material used and dispensing it in stripe form on the ground leaving a clear, distinct mark. Provisions having been made in the construction of the device to enable it to be turned in either direction at right angle to a straight line.

Another object of the invention is to provide a means that will accomplish the above and permit controlling the amount of marking material applied by a manual adjustment made by the operator.

Still another object of the invention is to provide a device of the character described that will, during the operation of applying the mark or stripe on the ground, keep the material used for marking agitated, thereby preventing the congealing or setting of the material, thus allowing an even mixture to be applied at all times.

The invention is fully described in the following specification of which the accompanying drawing is a part and in which the separate parts of my improvements are designated by suitable reference characters in each of the several views, and in which—

Fig. 1 shows a fragmentary cross sectional side view of the entire device, and

Fig. 2 shows a fragmentary cross sectional front view of the device.

Referring now to the drawing in detail wherein like characters of reference denote corresponding parts, the reference character 10, denotes a receptacle in which the marking material in liquid form is placed. This receptacle is provided with a cover 11, to keep the liquid material from splashing out of the top when the device is propelled over the ground.

The shaft 12, supports the agitator 13, consisting of a plurality of horizontally disposed arms joined at the ends by arms placed at right angle with the horizontal arms. This agitating assembly is supported by bearings 39 and 39A, respectively. The bearings 39, being equipped with a stuffing nut 40, holding a packing in place to prevent the liquid from escaping from the receptacle 10, through the bearing.

There is a driven sprocket 14, mounted on the shaft 12, and a chain 15, shown over the sprocket 14, is actuated by a drive sprocket 16, mounted on

device and engages the wheels 34, at both ends. The axle shaft 17, is mounted in adjustable bearings 18, having adjustment screws 33, to take up the slack of the drive chain 15.

The liquid material is dispensed from the receptacle 10, through the valve 19, equipped with a lever handle 20, mounted on the valve stem 21. This valve 19, when opened allows the liquid marking material to flow into a pivotally mounted spout 22, hinged at 23, on the brackets 35, and kept in position to contact the ground at all times by the tension exerted by the resilient member 31.

The entire unit is mounted on a frame consisting of a rearwardly disposed bracket 27, and the side supports 28 and 28A, respectively, which terminate into handles 32, at the top. There are rotatable mounted caster wheels 25, supported by yokes 24, and fastened at 26, on the frame. These casters swivel in the mounting 26, and allow for turning the entire device at right angles while being operated on the field.

The flexible cable shown at 29, fastened at one end to a hand operated lever at 30, engaging notches or grooves 38, in one of the handles, actuate the dispensing valve 19, allowing for adjustment in the control of the flow of liquid through the valve 19, out of the receptacle 10.

The device is further provided with an indicating medium 36, pivotally mounted at 37, providing a guide for the operator. This indicating medium 36, may be suspended on a chain or cable, not shown, when in a downward position off the ground so as not to interfere with the operation of the unit.

In operation the liquid marking material such as lime or paint is placed into the receptacle 10, and the cover 11, is closed to prevent splashing, the entire device is mounted on the wheels 34, and the casters 25, these will permit its being propelled over the ground by the operator who pushes on the handles 32. The indicating medium 36, is let down to a position an inch or two off the ground, as shown by dotted lines in Fig. 1. As the device is propelled along the ground the pivotally mounted spout 22, has its lower edge contacting the ground and the operator opens the valve 19, by means of the lever 30, inserting this lever into one of the plurality of slots 38, provided on the handle 32. These slots will hold the lever 30, which is attached to the flexible cable 29, in a fixed position and the flexible cable 29, actuating the valve lever 20, on the valve stem 21, opens or closes the valve 19.

In this manner a manually governed amount of liquid marking material is dispensed through the

valve 19, to the spout 22, which lays it onto the ground while the device is being propelled over the surface of the field.

5 While the device is in motion the drive sprockets 16, revolves the agitator 13, inside of the receptacle 10, by means of the drive chain 15, over the driven sprocket 14, which is fastened to the shaft 12, of the agitator 13. This will keep the marking material mixed, preventing the heavy particles from settling to the bottom of the receptacle. The indicating medium is used merely as an index to follow a line or guide on the ground for the convenience and efficiency of the operator.

10 15 The invention is susceptible to various changes in its form and minor details of construction, and the right is herein reserved to make such changes as properly fall within the scope of the appended claim.

20 Having thus described my invention, what I claim and desire to secure by Letters Patent in the United States, is:

In a device of the character described the com-

bination of a wheeled frame, a receptacle mounted on said frame, a shaft horizontally mounted in said receptacle, said shaft journaled in bearings mounted on the wall of said receptacle, agitating means mounted on said shaft within 5 said receptacle in close proximity to the bottom thereof, a sprocket mounted to a depending end of said shaft, a sprocket on the axle of said wheel frame, a chain engaging the sprocket on the axle and agitating shaft rendering said agitating operations when said axle is revolving, an outlet valve on the bottom of said receptacle, a spout pivotally supported from the bottom of said receptacle and underlying said outlet valve, a resilient member for depressing the rearwardly 10 directed discharge end of said spout toward the surface to be striped, an index control for opening said outlet valve, and a sight guide member projecting forward from said frame to guide the operation for accuracy in the operation of the 20 device.

DONALD JOHNSON.
